(57) **CLAIM**

The ornamental design for an MP3 player, as shown and described.

DESCRIPTION

FIG. 1 is a perspective view of an MP3 player according to my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the MP3 player according to our new design in a state in which the MP3 player is connected to necklace type earphones when used.

The broken line showing on FIG. 8 is for illustrative purposes only and forms no part of the claimed design.
